UNITED STATES PATENT OFFICE.

ISIDOR FLUEGELMAN, OF PHILADELPHIA, PENNSYLVANIA.

ELECTROMAGNETIC REGISTER.

No. 858,377.

Specification of Letters Patent.

Patented July 2, 1907.

Application filed June 7, 1906. Serial No. 320,677.

To all whom it may concern:

Be it known that I, ISIDOR FLUEGELMAN, a citizen of the United States, residing in the city and county of 5 Philadelphia, State of Pennsylvania, have invented a new and useful Improvement in Electromagnetic Registers, of which the following is a specification.

My invention relates to an electromagnetically actuated register or counter and the object of my invention 10 is to produce a counter of this type which shall be simple and cheap in construction; which shall be exceedingly compact and shall nevertheless give considerable amplitude and strength to the motion of the armature of the electromagnet which actuates the register; and in which all practical danger of having the 15 mechanical part of the register get out of order is obviated by utilizing any well tested construction of mechanical counter as may now be bought on the market at a moderate price.

20 To this end I take a soft iron casting comprising a base plate, the magnetic cores of the electromagnet, and a standard. To the base plate I pivot preferably a pair of arms connected by an armature swinging toward and from the cores in a plane normal thereto. I mount 25 a so-called Veeder counter on the back of the standard and actuate its operating ratchet wheel by a spring pawl secured to the swinging armature. The armature is pulled against the standard, as a stop, by a helical spring and the head of a screw taking in the standard 30 acts as a stop for the armature in the opposite direction.

The construction is strong and simple, the parts are compactly placed, the action is forceful, and there is practically no opportunity for things to get out of order.

In the drawings,—Figure 1 is a side elevation; Fig. 35 2 is a front elevation; and Fig. 3 is a plan of my electromagnetically actuated counter.

The frame is composed of a casting comprising a base plate A and a standard A², the cores A' carrying electromagnets A⁶ being either cast in one piece or otherwise rigidly secured to the base plate A. Two upright arms B' are connected by an armature B and are pivoted to the base plate at B² so that the armature swings in what may be considered a plane normal to the cores A'. The armature carries an arm B⁴ to which is connected a spring C by means of which the armature is pulled against the standard A², which thus acts as a stop. When, however, the magnets are energized, the armature is pulled against the tension of this spring until it abuts against the head of a stop-screw A³ which 45 takes into the top of the standard A². So much for the electromagnetic part of my register.

Upon the front of the standard A², I mount a common form of mechanical counter D, such as the well known Veeder pattern, which can be bought upon the market and which is compact and of approved efficiency. The operating shaft of this counter carries a ratchet D', each step of the ratchet wheel moving the counter one unit, as well known in the art. I mount a spring pawl B⁵ coöperating with the ratchet D', upon the armature B. Each time the electromagnets are 55 energized, the armature is thrown to the left, in Fig. 1, until it abuts against the stop-screw A³. This turns the ratchet D' one step and adds one unit to the number displayed on the register. The magnet being de-energized, the spring C pulls the armature back against 60 the standard, the pawl B⁵ slipping over a tooth of the ratchet D' ready to take a fresh hold the next time the magnet is energized.

By mounting the armature upon a pair of arms pivoted to the base plate, and by thus making it swing 70 over the tops of the cores in a plane normal to their axis, it will be seen that I impart sufficient motion to the armature to be able to connect it directly, by means of a pawl, with a fairly large ratchet operating the mechanical counter, thus increasing the certainty of the operation. 75 In this way, too, I am enabled to mount the counter on one side of the standard, the armature being stopped by the other side. While I prefer two electromagnets, as shown, one may be used.

I claim:—

1. An electromagnetic counter comprising a base plate, a core carrying an electromagnet and a standard, each rising from the base plate, a mechanical counter carrying an operating ratchet secured at or near the end of the standard opposite the base plate, an arm or arms pivoted 85 to the base plate supporting an armature moving over the core in a plane normal thereto, and a pawl on the armature coöperating with the ratchet, substantially as described.

2. An electromagnetic counter comprising a base plate, 90 a core carrying an electromagnet and a standard, each rising from the base plate, a mechanical counter carrying an operating ratchet secured to the upper end of the standard, a pair of pivoted arms supporting an armature moving over the core in a plane normal thereto, a pawl on the armature coöperating with the ratchet, and a headed screw taking into the standard, the screw head and standard acting as limiting stops for the motion of the armature, substantially as described.

3. An electromagnetic counter comprising a base plate, 100 a core carrying an electromagnet and a standard, each rising from the base plate, a mechanical counter carrying an operating ratchet secured at or near the end of the standard opposite the base plate, an arm or arms pivoted to the base plate supporting an armature moving over the core in a plane normal thereto, a pawl on the armature coöperating with the ratchet, an arm on the armature, a 105

helical spring connecting the arm and the standard, and stops limiting the motion of the armature in each direction, substantially as described.

4. An electromagnetic counter comprising a casting composed of a base plate from which rise a core carrying an electromagnet and a standard; a mechanical counter carrying an operating ratchet secured at or near the end of the standard opposite the base plate, a pair of arms pivoted to the base plate supporting an armature moving

over the core in a plane normal thereto, and a pawl on the armature coöperating with the ratchet, substantially as described.

In testimony whereof I have signed my name to this specification in the presence of two subscribing witnesses.

ISIDOR FLUEGELMAN.
